UNITED STATES PATENT OFFICE.

FRANK LEO KEHOE, OF POINT ARENA, CALIFORNIA.

GAME-BOARD.

1,184,538.

Specification of Letters Patent. Patented May 23, 1916.

Application filed October 29, 1915. Serial No. 58,685.

To all whom it may concern:

Be it known that I, FRANK LEO KEHOE, a citizen of the United States, residing at Point Arena, in the county of Mendocino and State of California, have invented new and useful Improvements in Game-Boards, of which the following is a specification.

This invention relates to game boards and it consists in the novel features hereinafter 10 described and claimed.

An object of the invention is to provide a board having paths and pockets provided thereon and adapted to be used in combination with a ball to simulate the plays of the 15 usual game of baseball.

With this object in view the board includes a base panel with bounding strips extended along the edges and positioned at one side thereof. The said strips are provided at their inner sides with pockets, and the field between the inner edges of the strips is divided into paths or channels by spaced blocks mounted upon the surface of the said panel. The edges of the said strips 25 are bounded by upstanding flanges. A ball is adapted to be used in combination with the said board, and in carrying out the game, the ball is initially positioned at or in the block which signifies the pitcher's station. 30 The board is then tilted to cause the ball to roll toward the batter's or catcher's station, and then the board may be tilted in another direction, whereby the ball is caused to roll along the paths or channels toward the in or 35 out field. Pieces are provided in combination with the board and may be positioned at or near the bases in order to indicate the progress made by base runners.

In the accompanying drawing:—Figure 1 40 is a plan view of the board. Fig. 2 is a longitudinal sectional view of the same cut on the line 2—2 of Fig. 1. Fig. 3 is a detail view of the ball. Fig. 4 is a similar view of one of the pieces.

The board includes a base panel 1, preferably of wood, with strips 2 positioned at the edges thereof, and against one side thereof. The outer edges of the strips 2 are bounded by upstanding flanges 3. Oblong 45 blocks 4 are mounted upon the surface of the panel 1 between the strips 2. The said blocks are spaced from each other and the blocks at one side of a diagonal line extending from one corner of the panel 4 to 50 the opposite corner are spaced from the

blocks at the other side of the said line, whereby a path or channel 5 is provided. The inner ends of the blocks at the opposite sides of the said path converge toward each other. An oblong block 6 is mounted upon the panel 1 at or about the pitcher's station, and the said block is provided at one end with a recess 7, which is in longitudinal alinement with the path 5. Pockets 8 are provided at the inner edges of the strips 60 2 in the vicinity of the batter's or catcher's position, and one of the said pockets is in longitudinal alinement with the path 5. Suitable legends are printed or otherwise applied to the strips 2 adjacent the pockets 65 70 8 and these legends may indicate strikes or a hit as shown in Fig. 1 of the drawing. The blocks 4 and 6 are those that will be referred to hereinafter as the in-field blocks. Blocks 9 are also mounted upon the upper 75 surface of the panel 1. The said blocks are oblong in plan and some of them are provided at their forward ends with pockets 10. The blocks 9 are disposed beyond the blocks 4 and 6, and are the blocks herein- 80 after referred to as the outfield blocks. The outfield blocks are spaced from each other and spaced from the infield blocks 4. The forward ends of some of the outfield blocks 9 enter the spaces between the adjacent 85 blocks 4 and the outer ends of some of the infield blocks 4 are disposed in the entrances of the pockets 10 of those blocks 9 provided with the said pockets. Those of the outfield blocks 9 which are provided with the 90 pockets 10, are also provided with legends as for instance "Out" and "One base hit".

The strips 2 which bound the outfield of the board are provided at their inner edges with pockets 11, and recesses 12. The 95 pockets 11 are wider at their inner ends than at their outer ends and the recesses 12 are substantially the same width throughout their length. The said pockets 11 and recesses 12 are alternately arranged with 100 relation to each other, that is to say, the recesses occur between the pockets and vice versa. The outer ends of the outfield blocks 9 enter the ends of the pockets 11 and the strips 2 provided with the pockets 11 and recesses 12 are further provided adjacent 105 the said pockets and recesses with suitable legends as for instance "Out", "Home run", "Three base hit", "One base hit", and "Two base hit". The strips 2 are pro- 110

vided in the vicinity of the points upon the board indicating first base, second base, and third base with holes 13 in which a piece 14 may be positioned. A ball 15 is 5 adapted to be used in conjunction with the board hereinbefore described.

To use the board the ball 15 is placed in the recess 7 of the block 6. The board is taken in the hands and is tilted so that the 10 ball 15 may travel along the path 5 toward the pockets 8. If the ball enters either of the pockets 8 adjacent which the legend "Strike" is positioned, this counts against the player and if three strikes are had in 15 three successive tiltings of the board, the player is out. If, on the other hand, the ball 15 enters the pocket 8 adjacent which the legend "Hit" is placed, this indicates that the player is entitled to place a piece 20 14 in the hole 13 adjacent first base. Should the ball lodge in the pocket 8 which bears the legend "Hit" the board may be tilted in a direction to cause the ball to gravitate out of the said pocket and move along the 25 patch 5 or through the spaces between the infield blocks 4. If the ball, as it moves toward the blocks 10 enters one of the pockets therein, the player is out, or his piece remains at first base according to 30 the legend adjacent that pocket which is entered by the ball. Should the ball pass through one of the spaces between the out- 35 field blocks 9 and enter one of the pockets 11 or one of the recesses 12, the advance of the piece of the player may be made accordingly. That is to say, if the ball enters the "Home run" recess, the player counts one score. If the ball enters "Third 40 base" recess the piece is advanced to the hole 13 adjacent third base. If the ball enters a pocket designated "One base hit" the piece is positioned in the hole adjacent first base and if the ball enters a pocket 45 designated "Two base hit" the piece is placed in the hole adjacent second base. It will be seen that if pieces occupy any of the holes adjacent first, second or third base, these pieces are advanced around the bases and toward "home plate" as a succeeding

piece gains position at either one of the said 50 bases.

From the above description taken in conjunction with the accompanying drawing it will be seen that a board of simple structure is provided and the same may be easily manipulated to simulate the plays of the usual 55 game of base ball.

Having described the invention what is claimed is:—

1. A game board comprising a panel, 60 strips mounted upon the panel and provided at their inner edges with pockets and recesses, infield blocks arranged in spaced relation upon the panel between the strips one of the said blocks indicating the pitcher's 65 block and being provided with a recess, outfield blocks also positioned upon the panel, some of the outfield blocks having pockets, some of the infield blocks having ends entering the pockets of the outfield 70 blocks and the ends of the outfield blocks entering the pockets at the edges of the outfield strips.

2. A game board comprising a panel, 75 strips mounted upon the panel and provided at their inner edges with pockets and recesses, said strips having positions indicative of first, second and third base and provided adjacent said positions with holes, a piece adapted to be positioned in the holes, 80 a ball adapted to be used in conjunction with the board, infield blocks mounted upon the panel in spaced relation and including a pitcher's block having a recess, outfield blocks mounted upon the panel, some of the 85 outfield blocks being provided at their ends with pockets, the outer ends of some of the infield blocks entering the pockets of the outfield blocks, the outer ends of the outfield blocks entering the pockets of the 90 strips which bound the outfield of the board.

In testimony whereof I affix my signature in presence of two witnesses.

FRANK LEO KEHOE.
